4 Claims. (Cl. 12—69.5)

1

This invention is concerned with improvements in machines for lacing shoe uppers, of the type disclosed in United States Letters Patent No. 962,105 granted June 21, 1910 on application of W. A. Smith. The illustrative machine is arranged to lace together two shoe upper parts by a continuous cord passed through eyelet holes in the parts with its ends tied together.

In the machine disclosed in said patent a row of parallel side-opening needles is provided, which when the machine has stopped after having operated on a workpiece support a series of cord loops which are drawn back between the needles by looper fingers and the eyelet holes of two shoe upper parts may be impaled by the loop supporting needles so that the needles and loops of cord project through the eyelet holes. The cord is then passed through the loops at the opposite side of the work from that at which the looper fingers act and the ends of the cord are knotted together. The two parts of the upper then completely laced together are thrust by the looper fingers from the needles.

In the machine disclosed in said patent the axes of the needles all are aligned in one flat plane and eyelet holes in shoe upper parts usually lie in a straight line so that no difficulty is experienced in impaling the holes on the needles. However, it has been found that the eyelet holes in some pairs of shoe upper parts do not form a straight row but lie in a somewhat curved row. In such cases difficulty may be experienced in impaling the eyelet holes on the needles, particularly if the material of the shoe upper parts is relatively stiff.

One of the various objects of the invention is to enable shoe upper parts having eyelet holes therein lying in curved or irregularly shaped rows readily to be laced together in a machine having a row of needles adapted simultaneously to be engaged by the eyelet holes.

The illustrative machine hereinafter described, which is generally similar to the machine disclosed in said patent, has four needles instead of five, corresponding to the needles referred to as the needles 25, in said prior patent. The needles at each end of the row of four needles in the illustrative machine are arranged to lie, when shoe upper parts are presented thereto, slightly lower by about one-sixteenth of an inch than the two center needles. With this arrangement the needles are so positioned that eyelet holes which lie in a somewhat curved row in the shoe upper parts may readily be impaled by the needles without distorting the shoe

2

upper parts or straining the needles excessively.

As disclosed in the patent above referred to the row of needles is mounted on spindles which are rotated about their own axes through ninety degrees during operation of the machine so that in one position of the needles the lacing cord may be laid across the needles by a cord-feeding needle, similar to that referred to at 86 in the patent, and drawn by the looper fingers into their side openings. When the needles are rotated into their other positions the cord-feeding needle may pass through the loops carried on the needle row after the work has been impaled.

The two endmost needles in the illustrative machine hereinafter described are eccentrically mounted in their spindles. When the four needles are in position to have the cord laid across them each endmost needle lies at one side of the axis of its spindle and the four needles of the row all lie in the same general plane with their hooks uppermost. When the four needle spindles have been rotated through ninety degrees from this position the needles are in position to have a curved row of eyelet holes placed upon them and the two endmost needles, owing to their eccentricity, have been moved into lower positions than the two middle needles and lie below the axes of their spindles so that the work may readily be applied to the needles. After the work has been applied to the needles the cord-feeding needle is caused to pass through the portions of the loops which lie in front of the work, the two endmost needles, or at any rate their front end portions, being brought up into line with the two center needles (so that the cord-feeding needle can pass through the loops) by a member, corresponding to the member referred to as the main member 177 in the prior patent. This member, as it is moved rearwardly to press the work on to the needles, bends the front portions of the two endmost needles into line with the center needles.

These and other features of the invention, as hereinafter described and claimed will readily be apparent from the following detailed description and accompanying drawings in which:

Fig. 1 is a view in right side elevation of the forward portion of a shoe upper lacing machine embodying the features of the present invention;

Fig. 2 is a view in front elevation of the same parts of the machine;

Fig. 3 is a detail view on an enlarged scale of the lacing needles and their supporting

spindles as seen in endwise relation while the needles are in positions to receive a lacing cord;

Fig. 4 is a similar view, indicating the relationship to the needles of a shoe upper having a curved row of eyelets just impaled by the needles;

Fig. 5 is a similar view of the same parts showing the positions of the needles when deflected into alinement during the lacing operation;

Fig. 6 is a detail view in side elevation of the row of needles showing the action of the needle deflector; and

Fig. 7 is a right side view on a reduced scale, partly in section, of certain portions of the machine illustrated in Fig. 1 taken while the needle deflector is acting.

The illustrated machine is generally similar to that disclosed in the Smith patent above identified. The patented machine is equipped with a straight row of five parallel eyelet entering needles identified at 25 in the patent. In the present machine, however, there are only four eyelet entering needles. These needles have mountings in which they are clamped at their rearward ends in a row of spindles mounted in the machine for rotary movement between two limiting position at an angle of approximately ninety degrees to each other.

Referring more particularly to the drawings the eyelet entering needles are indicated at 10 and are formed at their sides near their outer ends with slots or eyes 12 (see Fig. 6) which extend lengthwise of each needle for a short distance and open at the side of each needle with a diametral throat to receive and retain a lacing cord when the cord is pressed laterally against the needle and is carried rearwardly toward the clamped end of the needle. In one rotary position each needle has its throat alined with the others in the row. In the other rotary position each throat extends at right angles to the row. The spindles are illustrated at 14 and are rotatably mounted in a portion of the machine frame, indicated at 16. At their forward ends the spindles carry chucks comprising needle mountings, the center ones of which are indicated at 17.

At the rearward end of each spindle 14 is a crank 18 (see Fig. 1) having a crank pin 20 by which each spindle is rotated by mechanism including a slotted actuating bar 22 running across the rearward ends of all the crank pins 20, which crank pins are received within the slot of the bar. The ends of the bar are pivotally supported in the extremities of a pair of angle levers, one of which is illustrated at 24, fulcrumed on a fixed pin 26 and engaged at their upper ends within sockets provided in a reciprocable plate 28. The plate 28 projects forwardly and supports at its forward end a set of cooperating looper fingers 30. Each looper finger has its outer end bent downwardly across the row of needles and is interposed between an adjacent pair of needles. The arrangement of the needle rotating mechanism is such that after the lacing cord is engaged with the needles the looper fingers are retracted to form a series of loops in the lacing cord supported by the needles. The needles during this retraction are rotated through an angle of ninety degrees to a position with the throat of each needle at right angles to the row of needles to enable the operation of lacing the upper to be completed. As thus far described the machine is the same as disclosed in the Smith patent to which reference may be had for a better understanding.

If an attempt is made to impale a curved row of eyelets in an upper, such as is indicated at 32 by the broken lines in Fig. 4, on the straight row of needles of the patented machine, either the needles will be deflected from their proper positions in an irregular manner or the upper will be distorted from its flat condition so as to interfere with the proper operation of the machine. In any event it may be difficult to apply the eyelets to the needles so that special attention by the operator may be required and loss of time may result.

To enable easy application to the eyelet entering needles 10 in the present machine of a shoe upper having eyelets arranged in a row with curved formation, as shown by the dot dash line 34 of Fig. 4, the two center chucks 17 provide a mounting for their needles concentric to the axis of rotation of the respective spindles but the two end needles of the row are clamped in eccentric mounting chucks 35 on their spindles, the eccentric chucks providing an offset for the needles from the axes of their supporting spindles by about one sixteenth of an inch. The direction of offset displacement of the end needles is the same and at right angles to the needle row when the needles are in their rotary position with their cord receiving throats at right angles to the needle row. When the needles are in rotary positions with their throats in alinement with the needle row they are ready to have applied to them the lacing cord, all the needles being alined in the same general plane. In the latter rotary positions of the eyelet entering needles 10 the lacing cord is applied to them by the movement of a straight cord feeding needle 36 across the ends of the eyelet entering needles. After applying the lacing cord to the eyelet entering needles the cord feeding needle retracts and the looper fingers are carried rearwardly to form loops in the cord. At the same time the needles 10 are given a ninety degree rotation from the positions of Fig. 3 to those of Fig. 4 and the machine comes to rest. In the last mentioned rotary positions of the needles 10 the throats of the cord receiving slots lie at right angles to the general line of the needle row and the needles are ready to impale the eyelets of the shoe upper 32 (Fig. 4). If the upper has its row of eyelets disposed in the curved line 34 as illustrated, the two end needles being displaced downwardly by the eccentricity of the mounting 35, they are in positions where they readily will enter the two end eyelets of the upper without distorting the upper or deflecting the needles.

After the upper has been applied to the eyelet entering needles 10 a main upper positioning member 38 is moved downwardly and rearwardly to cause the shoe upper to be disposed correctly along the lengths of the needles. The member 38 also is arranged to engage beneath the front end portions of the two end needles and to deflect these end portions until they are level with those of the two center needles. The cord feeding needle 36 then passes a second time across the eyelet entering needles through the loops of cord on the eyelet entering needles, as illustrated in Fig. 7. The two end needles are reduced somewhat in thickness in a heightwise direction near their supporting spindles in order that they may more readily be deflected upwardly by the positioning member 38.

After the cord feeding needle 36 has passed through the loops of cord on the eyelet entering needles 10 the cord is gripped, cut off and the two

ends of cord in the shoe upper parts are knotted together by mechanism similar to that disclosed in the prior patent. While the cord is being knotted the cord feeding needle retracts from the loops of cord and the upper is pushed off the eyelet entering needles by an advancing movement of the looper fingers 30 until the laced upper is freed from the machine. Before the machine comes to rest, however, the eyelet entering needles are rotated through ninety degrees back to their aligned positions of Fig. 3 and the cord feeding needle thereafter moves across the eyelet entering needles to reengage the cord with their throats. The looper fingers then retract, forming loops in the cord after which the needles are returned to their stationary positions forming a curved row, again ready for entry into a curved row of eyelets.

The nature and scope of the invention having been indicated and a particular embodiment having been described what it claimed is:

1. A machine for lacing shoe uppers having a row of parallel needles, means cooperating therewith to form a series of loops in a lacing cord, rotatable spindles to which the needles are clamped and mechanism for rotating each spindle between two positions at an angle to each other, in combination with mountings for the needles on the spindles in which each end needle of the row is disposed eccentrically to the centers of rotation of the respective spindles to bring the needles into a curved row when in one rotary position.

2. A machine for lacing shoe uppers having a row of parallel needles, means cooperating therewith to form a series of loops in a lacing cord, rotatable spindles to which the needles are clamped and mechanism for rotating each spindle between two positions at an angle to each other, in combination with mountings for the needles on the spindles in which each end needle of the row is disposed eccentrically to the cen-

ters of rotation of the respective spindles to bring the needles into a curved row when in one rotary position and means for deflecting the two end needles from their curved row positions back into alignment with the remainder of the row to enable lacing of the upper to be completed.

3. A machine for lacing shoe uppers having a row of parallel needles, means cooperating therewith to form a series of loops in a lacing cord, rotatable spindles in which the needles are clamped and mechanism for rotating the spindles through angles of approximately ninety degrees, in combination with mountings for the needles on the spindles in which certain needles of the row are disposed eccentrically to the centers of rotation of their spindles in a direction at right angles to the row of needles when the spindles are in one rotary position and in a direction in the plane of the needle row when the spindles are in the other rotary position.

4. A machine for lacing shoe uppers having a row of parallel needles, means cooperating therewith to form a series of loops in a lacing cord, rotatable spindles in which the needles are clamped and mechanism for rotating the spindles through angles of approximately ninety degrees, in combination with mountings for the needles on the spindles in which certain needles of the row are disposed eccentrically to the centers of rotation of their spindles in a direction at right angles to the row of needles when the spindles are in one rotary position and in a direction in the plane of the needle row when the spindles are in the other rotary position and a deflector acting on the needles at the ends of the row to bring them back into line with the remainder of the row when the spindles are disposed in the first mentioned rotary position.

ARTHUR ALAN RIVINGTON.
